HANDED SHOPPING BAGS

Goble W. Bryant, Newburgh, N.Y., assignor to Interstate Bag Company, Inc., Walden, N.Y., a corporation of Virginia

Filed June 21, 1963, Ser. No. 289,493

2 Claims. (Cl. 229—54)

The present invention relates to handled shopping bags, and is to be regarded as an improvement on the bag described and claimed in the patent to Steen, 3,023,946 of March 6, 1962. In the patented bag construction, the top edge of the bag was provided with two oppositely located recesses with a score line formed about the upper margin which was parallel to, and spaced from the top edge a distance less than the depth of the recesses. The formation of the recesses also had the beneficial effect that the corresponding tabs which were created at the bottom of the bag facilitated the formation of the bag bottom, and effected a saving of paper. Since the score line was interrupted by the recesses, it followed that when the top flap was folded in, the folded edge was interrupted by the recesses, which thus did not provide a smooth edge for the entire periphery.

I have now discovered that by dropping the line drawn through the points at which the handle legs emerge from the retaining band a slight distance, it is possible to dispose the score line below the lower edge of the recesses so as to allow for an amount of bag material which may be infolded between the top of the recesses and the score line, thus producing a so-called full turn-top bag, i.e., one that has a smooth, turned edge around the entire periphery. In such a bag the advantage is had that the top of the bag, the flap having been infolded, is brought substantially nearer the line between the points of emergence of the handle legs from the retaining band, thus increasing the effective height of the handles above the top of the bag, and enabling the bag to contain an article which projects above the top of the bag a corresponding greater distance. In such manner, the capacity of the bag is thereby increased. Heretofore, when a full turn-top bag was had, the top edge of the bag was significantly higher from the line drawn through the points of emergence of the handle from the retaining band. In brief, I have now produced a turn-top bag which has a significantly greater capacity than the full turn-top bags heretofore made. At the same time, I have preserved the advantage of the embodiment according to Patent 3,023,946 as respects the formation of the bottom of the bag, and the saving of paper which is effected in its formation.

My invention will be best understood by reference to the following detailed description taken with the annexed drawings, in which

FIGURE 1 is a view of the upper portion of an illustrative bag embodying my invention, the foldable upper end flap of the bag being shown in part upstanding, and in part broken away and turned downward;

FIGURE 2 is an enlarged view taken on line 2—2 of FIGURE 1;

FIGURE 3 is a view on a reduced scale of the inner side of a complete unfolded blank with the handles and handle retaining and reinforcing bands attached; and

FIGURE 4 is a fragmentary diagrammatic view showing the web at successive stages of advance, and with sup-

2

plementary cuts indicated in broken lines as they will be applied toward the end of the blank formation.

Referring now to FIGURE 3, the blank 10 comprises body panels 12 and 14, a pair of gusset panels 16 and 18, and a second pair of gusset panels 20 and 22. The upper margins of the body panels 12 and 14 are formed with recesses 26 and 28 respectively; also twine handles 30 and 32 have their end portions adhesively secured between the body panels 12 and 14, respectively, and the reinforcing band 33 which may extend almost completely around the inside of the bag at a distance below the bottom of the recesses 26 and 28. This distance is of particular significance in this invention, i.e., it will accommodate a score line 34 upon which the top flap of the bag will be folded so as to include that portion of restricted height between said score line and the bottom line *a* of the recesses. Thus in practice, the reinforcing band 33 may be disposed an inch or more below said lines *a*, which will enable the entire top flap to be turned without difficulty.

Portions of the blank lying below the fold line 24 constitute the bottom forming material. Longitudinal fold lines 38, 40, 42, 44, 46 and 48 extend through the bottom and the body material from end to end of the blank. A further transverse fold line 50 extends across the blank in the bottom area. Short slits 52 are formed to extend upward from the bottom edge of the blank. Tongues or tabs 54 and 56, so created, extend downward beyond the normal lower boundary edges 57 of the blank, and are complementary respectively to the recesses 26 and 28. The bottom is also provided with diagonal fold lines 58, 59, 60 and 61. The bottom is in all respects conventional, save that the tabs or tongues 54 and 56 are rounded rather than angular as set forth in Patent 3,023,946. By making the tabs 54 and 56 complementary to the recesses 26 and 28, such flaps are provided at no extra expense of paper. In other words, the present improvement preserves this advantage as set forth in Patent 3,023,946.

40 In the manufacture of bags of this type, it is usual to slit the web along straight transverse lines extending completely across the handle zones, and short distances beyond them, so that each bag length can be separated from the web after the handles have been applied, by a 45 complementary partial severance confined to zones which are clear of the handles.

In the present instance, these cuts or partial severances are effected approximately an inch or slightly more beyond the upper boundary of the band 33, such slits being 50 denoted *b*, *b*. The second severance lines indicated as *c*, *c*, are spaced beyond the lines *b*, *b*, so as to give a turned-in flap of the usual width, say approximately 1½ inches, thereby creating a flap of this width except at the 55 region of the handles, wherein such dimension is reduced by the amount of encroachment of the cutouts. Here, although it will be noticed that these turned-in portions are of reduced width as compared with the rest of the flap, they are tucked back of the handle legs which operate to counteract any tendency of these short portions to stand away from the body of the bag.

Continuing the description of the bag making operation, adhesive stripes 63, FIGURE 4, are now deposited, that the cuts *b* are effected, followed by the formation of the score or fold line 34. Following this, the bands 33 bearing the handles 30 are deposited upon the adhesive

stripe 63 with the handles overlying the slits b, whereupon the top score lines c, having curved portions c' which connect with the cuts b, are effected. At the same time, longitudinal cuts 52 are made, as seen in FIGURE 3. When these operations have been performed, the bag 5 blanks are separated along the lines b, c' and c, in the usual manner by passing the web through rolls which, by giving the leading end of the web containing the blank a sudden pull, separates it from the remainder of the web. Thereafter, the blanks are formed into bags by conventional steps which are not necessary to describe here.

If desired, adhesive spots 65 and 67 may be provided, the purpose of which is to secure the folded flap in place. This turning of the flaps may be effected as the last step in the bag manufacture, and may be done manually, or 15 by mechanical means with which the present invention is not presently concerned.

While certain preferred embodiments of the invention have been illustrated and described in detail, it is to be understood that changes may be made therein and the 20 invention practiced in other forms without departing from the spirit of my invention or the scope of the appended claims.

I claim:

1. A handled shopping bag comprising a tubular body 25 having
  - two opposed sidewall sections,
  - a folded-over top edge and
  - a bottom folded structure, said top edge before being folded over being substantially straight save for 30 two oppositely located recesses formed in the upper margins of said two wall sections,
  - a score line formed about the upper margin of said body substantially parallel to and spaced from the top edge thereof a distance below the edge of said 35 recesses to permit folding of the upper margin of said tubular body to form an unbroken folded edge all the way round the top of the bag,
  - a pair of flexible looped handles having their end portions united to the inner faces of said side walls 40 below said score line and within the lower extent of said recesses with the handles extending up into the areas of said recesses enabling the handles to be grasped for carrying the bag with said upper margin infold,
  - a band disposed substantially parallel with the top 45

edge of the bag, and adhesively securing said handles to the bag, said band being spaced below said recesses by an amount such that when the top flap is turned in, the bottom edges of such recesses approximately meet said band.

2. A handled shopping bag comprising a tubular body having
  - two opposed sidewall sections,
  - a folded-over top edge and
  - a bottom folded structure, said top edge before being folded over being substantially straight save for two oppositely located recesses formed in the upper margins of said two wall sections,
  - a score line formed about the upper margin of said body substantially parallel to and spaced from the top edge thereof a distance below the edge of said recesses to permit folding of the upper margin of said tubular body to form an unbroken folded edge all the way round the top of the bag,
  - a pair of flexible looped handles having their end portions united to the inner faces of said side walls below said score line and within the lower extent of said recesses with the handles extending up into the areas of said recesses enabling the handles to be grasped for carrying the bag with said upper margin infolded, the lower end of the body being complementary to the upper end thereof and being infolded and adhered to form a rectangular bottom, the bottom edge of the body, though generally straight, being interrupted in its straightness by the inclusion of integral, protruding, adhesion tongues along opposite infolded and adhesively united sides of the bottom, which tongues substantially increase the area of overlap, and of adhesion, of said infolded sides of the bottom, and thereby serve to provide important reinforcement for the bottom, the tongues being complementary to the recesses in the upper end of the body, and being therefore provided at no extra expense of paper.
